METHOD OF MAKING MINING MACHINE CHAINS AND LINKS THEREFOR

Frank L. Fulke, Terre Haute, Ind., assignor to
 Frank Prox Company, Terre Haute, Ind., a corporation of Indiana

Application March 27, 1935, Serial No. 13,198

10 Claims. (Cl. 29—148)

The present application relates to methods of producing mining chains and links therefor. Primarily, the invention is concerned with the production of mining chains for various machines having various dimensions, that production to be as efficient as possible.

Further and more specifically stated objects of the invention will appear as the description proceeds.

To the accomplishment of the above and related objects, my invention may result in the production of the forms illustrated in the accompanying drawings, attention being called to the fact, however, that the drawings are illustrative only, and that change may be made in the specific construction illustrated and described, or in the specific steps stated, so long as the scope of the appended claims is not violated.

Fig. 1 is a more or less diagrammatic plan of 20 a section of a mining machine chain;

Fig. 2 is a diagrammatic composite view of four alternate links of a mining chain constructed in accordance with the present invention, the intermediate links having been omitted from the view 25 for clarity;

Fig. 3 is a side elevation of a completed link constructed in accordance with the invention;

Fig. 4 is an end view thereof;

Fig. 5 is a side elevation of a side strap adapted 30 to be associated with such link;

Fig. 6 is an end view thereof;

Fig. 7 is a side elevation of a forged blank from 35 which the link of Figs. 3 and 4 is to be made;

Fig. 8 is an end view thereof;

Fig. 9 is a view similar to Fig. 8, but showing 40 a different form of link, and indicating one manner of modifying the shape of such a link to adapt the same to machines of various dimensions;

Fig. 10 is a view similar to Fig. 9, and indicating another manner of modifying the shape of the link to adapt it to machines of various dimensions;

Fig. 11 is a side elevation of a third link-blank 45 shape;

Fig. 12 is an end view thereof; and

Fig. 13 is a side elevation, partly in section, of 50 a link shape, showing a method of providing a stop abutment for the cutter to be received in the cutter socket.

A mining machine, so called, is a large, preferably automotive, machine carrying at its front end a forwardly projecting arm or trackway upon which is supported a chain. A driven sprocket is positioned at the inner end of the trackway, and

an idler sprocket is carried at the extremity of the trackway, the chain being mounted to ride on said sprockets.

The chain consists of links, connected to each other by pairs of side straps, each of said links carrying a cutter. As the machine moves forward, the chain, riding over the trackway and the idler sprocket, brings the cutters into contact with the coal to cut a groove in advance of the machine.

It is customary to arrange the cutters of adjacent links of the chain in different planes with respect to the center of the chain, so that the chain will cut a groove of considerable width. This arrangement of the cutters requires the provision of heads on the cutter-carrying links, certain of said heads being offset laterally from the center plane of the chain.

At the present time, there are three major manufacturers of mining machines of this character; and each manufacturer has established a different set of dimensions for his cutter chain trackway. As produced by the machine manufacturers, these machines and their original chains vary also in other respects; viz., link 20 lengths, side strap lengths, diameters of and distances between connecting perforations, and widths of kerfs cut. In the past, it has been the universal practice of replacement chain manufacturers to reproduce these differences in manufacturing replacement chains for the several machines; but it is a feature of the present invention that I have consolidated all of the variable factors into a set of uniform dimensions, whereby 25 the same links and side straps may be used in the production of a chain for any one of the machines, subject only to variations in link thickness, as described.

I am engaged in the manufacture of cutter chains which I sell as replacements for cutter 40 chains worn out or broken in service on the machines manufactured by other parties.

Heretofore, it has been my practice, and the practice of other manufacturers in the same line of business, to form the links of such replacement chains of castings. As is shown in Fig. 2, it is desirable to have at least four different cutter positions on each side of the central vertical plane of the cutter chain. This has required the provision of eight castings for the links of each 45 chain. Since the dimensions of the trackways of the three major mining machines vary, it has been necessary to carry in stock different sizes of links to cooperate with the trackways of the respective machines. This has meant that the 50

10

20

25

30

35

40

45

50

55

manufacturer of replacement chains has had to carry in stock twenty-four different shapes of cutter chain links; which has, of course, required large storage space, and a relatively large investment in stock.

I have determined to initiate the use of forged links for my replacement cutter chains; the advantage of the use of such links being obvious.

Because of manufacturing methods, the cost, 10 per piece, of castings in lots of, for instance, fifty is not materially greater than the cost per piece in lots of a thousand. Nor is the cost of patterns used in casting operations particularly high. Therefore, it is not prohibitively extravagant for 15 a manufacturer of replacement chains to carry in stock a suitable number (twenty-five to a hundred or more) of each of twenty-four different link shapes.

But the cost per piece of forgings is very materially affected by the number of pieces produced in each lot. Not only is the cost of producing dies much greater than the cost of producing patterns, but the cost of setting up the dies in the forging machine is very considerable. When that 25 setting-up cost can be divided among several thousands of pieces produced from one set-up, it does not have too great an effect upon the cost per piece of the group; but its effect upon the piece cost becomes absolutely prohibitive if fewer 30 than, say, one thousand pieces are produced from a single set-up.

It will be readily apparent that the problem of stocking twenty-four different shapes is very different when the manufacturer must think in 35 terms of thousands rather than in terms of half-hundreds. Therefore, I have been forced to evolve a new method of manufacturing mining machine cutter chains and links therefor.

Referring more particularly to the drawings, 40 it will be seen that the chain, indicated generally at 10 in Fig. 1 of the drawings, is made up of a plurality of links, connected together by side straps. The link 11A is provided with a head offset to the right of the center of the chain; and 45 is provided with a cutter-receiving socket 12. The link 11A' is identical with the link 11A, except that its cutter-receiving socket 13 is disposed at a different angle to the vertical. The link 11B is provided with a head offset farther to the right, and is formed with a cutter-receiving socket 14. 50 The link 11B' is identical with the link 11B except that its cutter-receiving socket 15 is disposed at a different angle to the vertical.

Between the links 11A and 11A' there is disposed a link 11A'' which, in general configuration, is identical with the link 11A and is provided with a cutter-receiving socket 12 identical with the cutter-receiving socket of the link 11A; but the link 11A'' has been turned end for end with 55 respect to the link 11A before insertion in the chain. Between the links 11A' and 11B is disposed a link 11B'', said link being identical in general configuration with the link 11B and being formed with a cutter-receiving socket 14 identical with the socket 14 of the link 11B; but said link 11B'' has been turned end for end with respect to the link 11B before insertion in the chain. Between the links 11B and 11B' is disposed a link 11B''' identical in general configuration with the link 11B' and provided with a cutter-receiving socket 15 identical with the socket 15 of the link 11B'; but said link 11B''' has been turned end for end with respect to the link 11B' before insertion in the chain. Beyond 70 75 the link 11B' is disposed a link 11A''' identical

in configuration with the link 11A' and provided with a socket 13 identical with the socket 13 of the link 11A'; but the link 11A''' has been turned end for end with respect to the link 11A' before insertion in the chain.

Each pair of adjacent links is connected together by a pair of side straps 16, 17 in a manner later to be described.

In Fig. 7 is illustrated a link blank 11Y. Said blank comprises a head 18, and a main body 19, a base flange 20 projecting laterally from each side of the body 19, and two ears 21 and 22 projecting longitudinally from said body. The lateral thickness of the flange portion 20 is somewhat greater than the main body portion 19, and the lateral thickness of the ears 21 and 22 is somewhat less than the thickness of the body portion 19. The lateral dimension of the head 18 is unimportant.

It will be seen that the lateral surfaces of the ears 21 and 22 are generally circular, but that portions 23 and 24 are relieved to facilitate machining. This blank is formed by forging, the same being a solid block without perforations formed therein.

The forgings 11Y are formed with lateral thickness dimensions slightly greater than the largest lateral dimensions provided by any mining machine manufacturer. After the blanks have been formed, the ears are bored to provide 20 perforations 25 and 26 therethrough; and thereafter a cutter-receiving socket is formed in each blank.

I have found that the number of shapes required for any given mining machine may be materially reduced by varying the angle at which the cutter-receiving socket is formed in a single shape. I have found that cutter-receiving sockets may be formed on two different angles in any given link shape; and that idea is illustrated in 30 Fig. 2. The construction line associated with the cutter 12X of Fig. 2 represents the center line of the cutter-receiving socket formed in links like the link 11A. The construction line associated with the cutter 13X represents the center line of the cutter-receiving socket formed in links like the link 11A'. The construction line associated with the cutter 14X represents the center line of the cutter-receiving socket formed in links like the link 11B. The construction line associated with the cutter 15X represents the center line of the cutter-receiving socket formed in links like the link 11B'. 40 45 50

This method of forming cutter-receiving sockets in links halves the number of link shapes required for a given chain.

Each cutter-receiving socket is formed by drilling a hole 27 through the head 18 and body 19 of a link blank, such hole extending from the upper surface of the head 18 completely through the body portion. Thereafter, the opposite sides of the bore 27 are longitudinally broached to form rectangular grooves 28 and 29.

I then form a bore 30 opening from one end of the head 18 into the cutter-receiving socket; and said bore 30 is internally threaded for the reception of a set screw (not shown) adapted to engage and hold in place the cutter received in the socket. The hole 27 may be blocked, adjacent its lower end, by a pin 50 driven through a suitably formed hole in the body portion 19, whereby a portion of said pin is disposed within the cutter-receiving socket in blocking relation thereto. I shall describe hereinafter a modification 65 70 75 80 85 90 95 96 97 98 99 100

in this arrangement which I consider a very definite improvement thereon.

A further reduction in the number of shapes necessary for the production of a given size of chain can be effected by selecting the end of the head 18 through which the bore 30 is formed. That is, the links 11A'', 11A''', 11B'', and 11B''' differ from the links 11A, 11A', 11B, and 11B', respectively, only in that the bore 30 is formed 10 in the opposite end of the head 18 thereof.

In Fig. 5 is illustrated a forged side strap 16 which comprises a body portion 31 of a thickness substantially equal to one-half the thickness difference between the link body portion 19 and the link ears 21 and 22. Said strap is formed 15 with a base flange 32 projecting from one face thereof a distance substantially equal to one-half the thickness difference between the link body 19 and the link flange 20. Adjacent one end of 20 the opposite face of said body portion 31 there is formed a stud 33 projecting from said body face a distance substantially equal to one-half the thickness of the link ear portion 22. Adjacent the other end of said body portion there 25 projects from said last-mentioned face a second stud 34 of the same height. Perforations 35 and 36 are formed through said strap coaxial with the studs 33 and 34, respectively.

An ear 37 projects upwardly from the body 31 and is formed with a stud 38 of a height substantially equal to the height of the stud 33, a perforation 39 being formed through said ear coaxial with the stud 38. A rib 40 is preferably formed adjacent the upper edge of the body 31.

The side straps 16 are all alike; and the side straps 17 are also all alike, bearing an allochiral relation to said straps 16.

When a chain is to be assembled, the stud 33 of a strap 16 is entered in the perforation 26 of the ear 22 of each link; and the corresponding stud of a strap 17 is likewise entered in said perforation from the opposite side thereof; and a rivet is passed through the bores 35. Of course, before the straps 16 and 17 are riveted together, 45 the stud 34 of the strap 16 and the corresponding stud of the strap 17 are entered in the perforation 25 of the ear 21 of the next adjacent link; and a rivet is passed also through the bores 36. The studs 38 of the straps 16 and 17 will then be 50 in substantially abutting relation, and a rivet may be passed through the bores 39. The function of the ears 37 is to stiffen the chain.

As is indicated in Fig. 2, the chain trackway of a mining machine comprises a rail 41 formed 55 with a T-slot 43 enlarged at its base as at 42. The flanges 20 and 32 must fit within the enlargement 42, and the body portions 19 and 31 must fit within the portions 43 of the groove.

Because of the manner of forming the cutter-receiving sockets, and the manner of forming the set screw receiving bores 30, I am able to form a chain for any given machine, using only two different forged link shapes to accomplish the function of eight cast shapes heretofore used. 60 I have discovered that those two link shapes may not only be readily adapted to accomplish the functions of the eight castings heretofore used in the production of any one chain, but further may be used to produce chains for all of 65 the machines now on the market. Thus, instead of requiring the replacement chain manufacturer to carry in stock twenty-four different link shapes, I have made it possible for him to accomplish everything that he accomplished with 70 those twenty-four different link shapes, carrying 75

in stock only two different types of forged link blanks.

The arrangement described herein provides an eight-position chain in a manner which is, actually, unobjectionable. However, the practical art has long been accustomed to chains made of links in which the cutter-receiving socket is formed on an axis perpendicular to the top surface of the head, and it is possible that the practical art may not, therefore, take kindly to a chain in 10 which such sockets are formed, in some instances, on axes otherwise angularly related to the head surfaces. Obviously, it will be possible to overcome such objections while still retaining many of the advantages of my invention. 15 Thus, four blank shapes may be used, without forming cutter sockets at different angles in each shape, to provide a seven-position chain, and five blank shapes may be used to form a nine-position chain. 20

My blank 11Y is originally forged with its lateral dimensions slightly larger than the lateral dimensions of the largest mining machine trackway. Of course, the rough forging must be smoothed before use and the smoothing operation reduces the lateral dimensions of the blank to values best adapted for cooperation with that largest trackway. In order to adapt that same blank for use in a chain to be used in connection with any one of the other machines, 30 it is only necessary to reduce the lateral dimensions of the blank sufficiently to adapt that blank for association with the trackway of known dimensions. It happens that, in all three major machines, the lateral distance from one vertical 35 wall of the portion 42 of the trackway to the adjacent vertical wall of the portion 43 of the trackway is the same. Therefore, the thickness difference between the flange portion 20 and the body portion 19 of the link blank will remain a 40 constant, regardless of the machine with which the chain is intended to be used and as a further consequence, the degree of projection of the flange 32 from the face of the body 31 of the side straps need not vary. To adapt an original forging to a machine of smaller dimensions, therefore, the thickness of the flange portion 20 must be reduced to a proper value, and the thickness of the body portion 19 must be equally reduced. 45 Because of the thickness of the body portion 31 of the straps 16 and 17, it is desirable likewise to reduce the thickness of the ear portions 21 and 22 an equal amount. This requires reduction 50 of height of the studs 33, 34, and 38 an amount equal to substantially one-half the thickness reduction of the link portions. 55

A feature of importance in producing my chain consists in the fact that, if it is desired to maintain constant the lateral distance from each wall of the trackway to the adjacent edge of the kerf 60 to be cut by the machine, then the lateral distance from the adjacent surface of the link body to the point of the associated cutter must not be varied by the act of thickness reduction, particularly in view of the reversibility feature 65 of my links. Consequently, when the thickness-reduction principle is applied to a link having an offset head, the total reduction must be effected by machining that surface of the link opposite the offset of the head. 70

In Fig. 9 there is illustrated one manner in which the link may be so modified for association with various machines. The solid line 191 represents one surface of the body portion of the link when dimensioned for use with the largest ma- 75

chine; the dash-and-dot line 192 represents said surface when adapted for use with the intermediate machine; and the dotted line 193 represents that surface when intended for use with the smallest machine. The solid line 201 represents the flange surface when the link is intended for use with the largest machine; the dash-and-dot line 202 represents that surface when intended for use with the intermediate machine; and the dotted line 203 represents that surface when intended for use with the smallest machine. The solid line 221 represents one surface of a link ear when intended for association with the largest machine; the dash-and-dot line 222 represents that surface when intended for use with the intermediate machine; and the dotted line 223 represents that surface when intended for use with the smallest machine.

However, if it is desired to maintain constant the lateral distance from the median plane of the trackway to each edge of the kerf to be cut by the machine, then the thickness reduction must be effected by removing equal amounts of metal from each of the lateral surfaces of the link blank. In Fig. 10, there is illustrated this method of modifying the link shapes for association with various machines. In Fig. 10, the solid lines 194, 197, 204, 207, 224, and 227 represent the various opposite surfaces of the link when dimensioned for use with the largest machine; the dash-and-dot lines 195, 198, 205, 208, 225, and 228 represent those surfaces when the link is dimensioned for use with the intermediate machine; and the dotted lines 196, 199, 206, 209, 226, and 229 represent those surfaces when intended for use with the smallest machine. It will be seen that, according to this method, one-half the required thickness reduction is removed from each of the opposite surfaces of the link blank.

Obviously, the studs 33, 34, and 38 must be reduced in height sufficiently so that the projection of each stud from the body portion 31 will be equal to substantially one-half the thickness of the link ear portion.

Figs. 11 and 12 represent a further form of link which may be used, in case it is desired to obviate the necessity of using cutter-receiving sockets drilled at different angles in the link; such a link, indicated generally by the reference numeral 45, including a head 46 which is not offset. Such a link, of course, would carry a vertical cutter.

In Fig. 13, I have illustrated a method of producing a substitute for the pin 50 shown in Fig. 3.

After the bore 27 and the broached grooves 28 and 29 have been formed, a bar 47, snugly fitting said grooves 28 and 29, is inserted therein from the upper end of the cutter-receiving socket. Said bar 47 is provided with any desired means for limiting its degree of penetration into the socket, a head 48 being illustrated as such a means. The bar 47 is designed and dimensioned so that the end 49 thereof will, when the bar has been fully introduced into the socket, lie in the plane which is desirably occupied by the bottom end of the cutter which is adapted to be associated with the link. Thereupon, a weld rod 51 is introduced from the opposite end of the socket 27, and is brought into contact with a wall of the socket to deposit a shoulder or abutment 52 of metal thereagainst. The metal so deposited, will, of course, be welded integrally to the link body; and if the bar 47 is made of copper, the metal so deposited will not be welded to

the bar. Thus, the bar 47 may be readily withdrawn from the socket after the abutment 52 has been deposited.

The obvious simplicity of the above-described method of producing a stop for cutters, as compared with the provision of a stop such as the pin 50, will demonstrate the importance of this improvement; and it will be evident that dislodging or shearing off often encountered with the usual stop pins will be eliminated by my stop formed of solid metal deposited as an integral part of the link.

I claim as my invention:

1. The method of making a mining machine cutter chain link which includes the steps of forging a link blank shaped to provide a head and a plurality of portions of different thicknesses, each one of said last-named portions having at least one surface parallel to at least one surface of each other one of said last-named portions, and machining certain of said parallel surfaces to reduce the thicknesses of certain of said last-named portions to adapt said link for use with any selected one of various mining machines.

2. The method of making a mining machine cutter chain link which includes the steps of forging a link blank shaped to provide a head, a main body portion, a pair of oppositely longitudinally projecting ears of less lateral extent than said main body portion, and a pair of oppositely laterally projecting flanges of greater lateral extent than said main body portion, forming an aperture through each of said ears, forming a bit-receiving socket in said head, and reducing the lateral extent of said ears, said body portion, and said flanges to adapt said link to any selected one of a plurality of mining machines.

3. The method of making a mining machine cutter chain link which includes the steps of forging a link blank shaped to provide a head, a main body portion, a pair of oppositely longitudinally projecting ears of less lateral extent than said main body portion, and a pair of oppositely laterally projecting flanges of greater lateral extent than said main body portion, forming an aperture through each of said ears, forming a bit-receiving socket in said head and body portion, forming a threaded socket from one longitudinal end of said head and opening into said bit-receiving socket, and reducing the lateral extent of said ears, said body portion, and said flanges to adapt said link to any selected one of a plurality of mining machines.

4. The method of making a mining machine cutter chain link which includes the steps of forging a blank including a head and a body, and drilling a hole through said head and body, said hole opening through the upper surface of said head and having its axis disposed on any one of a plurality of predetermined angles to the vertical.

5. The method of making a mining machine cutter chain link which includes the steps of forging a blank including a head and a body, drilling a hole through said head and body, said hole opening through the upper surface of said head and having its axis disposed on any one of a plurality of predetermined angles to the vertical, and broaching rectangular grooves at longitudinally opposite sides of said hole.

6. The method of making a mining machine cutter chain link which includes the steps of forging a blank including a head and a body, drilling a hole through said head and body, said

5 hole opening through the upper surface of said head and having its axis disposed on any one of a plurality of predetermined angles to the vertical, broaching rectangular grooves at longitudinally opposite sides of said hole, and forming a threaded opening in said head, said opening leading from one longitudinal end of said head into said drilled hole.

10 7. The method of making a mining machine cutter chain link which includes the steps of forging a blank including a head and a body, drilling a hole through said head and body, said hole opening through the upper surface of said head and having its axis disposed on any one of a plurality of predetermined angles to the vertical, and flowing a gob of metal in molten condition into said hole at a point remote from said head, to form a stop for a cutter received in said first-named hole.

15 8. The method of making mining machine cutter chains for use with any selected one of a plurality of mining machines, which includes the steps of forging a plurality of link blanks, each comprising a head, a main body, a lateral flange adjacent the base of said main body, and a pair of terminal ears, said body being of less thickness than said flange and said ears being of less thickness than said body, perforating said ears, forging a plurality of side straps, two for each link, each comprising a body portion of a thickness substantially equal to one-half the thickness difference between said link body and said ears, a flange projecting from said strap body a distance substantially equal to one-half the thickness difference between said link body and said link flange, and a pair of studs, one adjacent each end of said strap body and projecting therefrom a distance substantially equal to one-half the thickness of said ears, machining one 20 surface of each link body, link flange, and link ear, to reduce the thickness thereof in equal amounts, machining said strap studs to reduce the thickness thereof by one-half such amount to adapt said links and straps to the selected 25 machine, and associating a pair of straps with each two adjacent links by entering said strap studs in said link ear perforations.

30 9. The method of making mining machine cutter chain link which includes the steps of producing a link formed with a cutter-receiving socket open at both ends, inserting into one end of said socket a copper bar, and inserting into the other end of said socket a welding rod to deposit a gob of metal on a wall of said socket 35 against said bar.

40 FRANK L. FULKE.

thickness thereof an equal amount, machining said strap studs to reduce the thickness thereof by one-half such amount, and associating a pair of straps with each two adjacent links by entering said strap studs in said link ear perforations. 5

10 9. The method of making mining machine cutter chains for use with any selected one of a plurality of mining machines, which includes the steps of forging a plurality of link blanks, each comprising a head, a main body, a lateral flange adjacent the base of said main body, and a pair of terminal ears, said body being of less thickness than said flange and said ears being of less thickness than said body, perforating said ears, forging a plurality of side straps, two for each link, each comprising a body portion of a thickness substantially equal to one-half the thickness difference between said link body and said ears, a flange projecting from said strap body a distance substantially equal to one-half the thickness difference between said link body and said link flange, and a pair of studs, one adjacent each end of said strap body and projecting therefrom a distance substantially equal to one-half the thickness of said ears, machining one 15 surface of each link body, link flange, and link ear, to reduce the thickness thereof in equal amounts, machining said strap studs to reduce the thickness thereof by one-half such amount to adapt said links and straps to the selected 20 machine, and associating a pair of straps with each two adjacent links by entering said strap studs in said link ear perforations.

25 10. The method of making a mining machine cutter chain link which includes the steps of producing a link formed with a cutter-receiving socket open at both ends, inserting into one end of said socket a copper bar, and inserting into the other end of said socket a welding rod to deposit a gob of metal on a wall of said socket 30 against said bar.

40 FRANK L. FULKE.
